H. A. DOUGLAS,
CIRCUIT CONNECTOR SWITCH,
APPLICATION FILED AUG. 23, 1917.

1,261,790.

Patented Apr. 9, 1918.

Inventor
Harry A. Douglas
by G. L. Gray

UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

CIRCUIT-CONNECTOR SWITCH.

1,261,790.

Specification of Letters Patent. Patented Apr. 9, 1918.

Application filed August 23, 1917. Serial No. 187,794.

To all whom it may concern:

Be it known that I, HARRY A. DOUGLAS, a citizen of the United States, residing at Bronson, in the county of Branch and State of Michigan, have invented a certain new and useful Improvement in Circuit-Connector Switches, of which the following is a full, clear, concise, and exact description.

My invention relates to circuit connectors that are also constructed to function as switches and is an improvement upon the connector switch claimed in my Patent No. 1,220,139, dated March 20, 1917. The switch disclosed in my aforesaid patent included a shell having bayonet slots at the ends thereof, the bayonet slot at one end having two bayonet pin engaging seats spaced apart longitudinally of the shell, contact carriers at the ends of the shell and having bayonet pins engageable with the seats in the bayonet slots, an intermediate contact carrier within the shell and carrying contacts upon the ends thereof which are engageable with the contacts upon the aforesaid contact carriers, the contact element upon the end of the intermediate contact carrier that is adjacent that end of the shell whose bayonet slot has two seats being substantially co-axial with the shell, an abutment surrounding the latter contact and having a cup-shaped portion engaging the carrier at the latter end of the shell and surrounding the contact upon this carrier that is complementary to the contiguous contact upon the intermediate carrier, and a spring maintaining pressure of the abutment against the end contact carrier engaged by the abutment.

In practising my present invention, the contacts upon the ends of the intermediate contact carrier have telescoping engagement with each other, both of these contacts being sliding contacts and one at least being a tubular contact in which the other is telescopically received. These telescoping contacts have motion limiting formations whereby the extent to which they may be spread apart is limited, and whereby one of these contacts is prevented from following the end contact carrier, that has inner and outer bayonet slot seats, to its outer position so that when this end contact carrier is in such outer position the circuit is opened.

These and other characteristics of my in-

vention will be fully set forth by reference to the preferred embodiment thereof shown by the accompanying drawing in which Figure 1 is a view partially in elevation and partially in section illustrating a form of my invention, that plug which is adjustable longitudinally of the shell being shown in its inner position; Fig. 2 is a view similar to Fig. 1 but showing the longitudinally adjustable plug in its outer position; Fig. 3 is a longitudinal sectional view of the structure minus the end contact carriers; Fig. 4 is an end view looking at the right hand end of the construction as it appears in Fig. 3; and Fig. 5 is a view on line 5—5 of Fig. 3.

Like parts are indicated by similar characters of reference throughout the different figures.

The switch of my invention includes a metallic current conducting shell 1 having bayonet slots 2 and 3 in the ends thereof. The bayonet slot 2 has one bayonet pin engaging seat 4 while the bayonet slot 3 has an inner bayonet slot seat 5 and an outer bayonet slot seat 6, these bayonet slot seats 5 and 6 being spaced apart longitudinally of the shell. In the preferred embodiment of the invention there are two bayonet slots 2 each with its seat 4 and two bayonet slots 3 each with its seats 5 and 6. An end contact carrier 7 has bayonet pins 8 projecting therefrom which are receivable in the bayonet slots 2 and the seats 4 provided in these slots. An end contact carrier 9 has bayonet pins 10 projecting therefrom which are receivable in the bayonet slots 3 and the seats 5 and 6 provided in these slots. The contact carrier 7 includes an inclosing metallic sheath 11 that constitutes one terminal of the lamp filament 12 of the lamp 13 carried by the contact carrier 7. The contact carrier 9 includes an inclosing metallic sheath 14 that constitutes one terminal of one of the conductors 15 leading to a source of current. The sheaths 11 and 14 have electrical contact with the metallic shell 1 whereby the conductor 15 is connected with one terminal of the lamp filament 12. The contact carrier 7 carries a central contact 16 constituting the remaining terminal of the lamp filament 12. The contact carrier 9 carries a central contact 17 constituting a terminal of the conductor 18 extending from the source of current that is included between this conductor and the conductor 15.

I provide an intermediate contact carrier 19 within the shell in a mid-position between the end contact carriers 7 and 9. This intermediate contact has a central 5 opening extending longitudinally of the shell. There is a tubular sliding contact 20 for engagement with the central contact 17 upon the end carrier 9, this tubular sliding contact having sliding engagement with the 10 intermediate contact carrier in the central opening therein. This sliding contact also has motion limiting formations or flanges 21, 22 that are engageable with the intermediate contact carrier and between which the 15 intermediate contact carrier is disposed. A second tubular sliding contact 23, in electrical connection with the contact 20, also movable longitudinally of the shell, is in telescoping engagement with the other sliding 20 contact 20, these sliding contacts having interengaging motion limiting formations 24, 25 whereby the extent to which these contacts may be outwardly extended with respect to each other is limited. A 25 spring 26 is disposed within the tubular sliding contacts and operates to press outwardly upon these contacts to engage each one with the central contact upon the adjacent end contact carrier. There is a cup-shaped abutment 27 at the end of the shell that has the two bayonet seated slots 3. This abutment is spaced apart, by an annular space, from the central contact 17 and also surrounds the sliding contact 20. 30 The motion limiting formation 21 upon the sliding contact 20 permits engagement between the central contact 17 and the sliding contact 20 when the contact carrier 9 is in its inner position, but when this contact carrier 9 is being placed in its outer position the motion limiting formation 21 engages the intermediate contact carrier 19 before the contact carrier 9 reaches its outer position so that when such contact carrier 40 has reached its outer position the contact 20 is held out of engagement with the contact 17 to open the circuit of the lamp, it being understood that the lamp circuit is closed when the carrier 9 is in its inner position by way of the electrically connected contacts 20 and 23 and the central contacts 17 and 16 respectively engaged thereby. A 45 spring 28 is interposed between the intermediate contact carrier 19 and the cup-shaped abutment 27 to maintain this abutment in engagement with the end contact carrier 9 while this end contact carrier is in either of its inner or outer positions. This abutment supplements the spring 26 in its 50 function of maintaining the pins of the end contact carriers firmly in their bayonet seats when the contact carrier 9 is in its inner position. When the contact carrier 9 is in its outer position the spring 55 60 65 70 75 80 85 90 95 100 105 110 115 120 125 130 26 functions only to hold the end contact

carrier 7 in engagement with its bayonet seats, this spring performing this function through the intermediation of the tubular contact 20 and the flange 21 that is then pressed by this spring against the intermediate contact carrier 19. The spring 28 serves to hold the contact carrier 9 in its outer bayonet seats 6 to maintain assembly of this contact carrier and the shell while the lamp circuit is opened. The cup-shaped abutment and the sliding contact 20 which it surrounds have interengagement (due to the flange 22 upon the contact 20) that prevents this switching contact and abutment from becoming separated but permits the cup-shaped abutment to maintain engagement with the end contact carrier when this carrier is in its outer position.

Having thus described my invention I claim as new and desire to secure by Letters Patent the following:

A switch including a shell having bayonet slots at the ends thereof, the bayonet slot at one end having two bayonet pin engaging seats spaced apart longitudinally of the shell; end contact carriers at the ends of the shell and having bayonet pins engageable with the seats in the bayonet slots; central contacts upon the inner ends of said end contact carriers; an intermediate contact carrier within the shell and provided with a central opening extending longitudinally of the shell; a tubular sliding contact for engagement with the central contact upon one of the end contact carriers and having sliding engagement with the intermediate contact carrier in the central opening therein; this tubular sliding contact having motion limiting formations engageable with the intermediate contact carrier and between which the intermediate carrier is disposed; a second sliding contact movable longitudinally of the shell and in telescoping engagement with the other sliding contact, these sliding contacts having interengaging motion limiting formations whereby the extent to which they may be outwardly extended with respect to each other is limited; a spring within the aforementioned tubular sliding contact and operating to press outwardly upon the sliding contacts to engage each sliding contact with the central contact, upon the adjacent end contact carrier; a cup-shaped abutment at the end of the shell that has the two seated bayonet slot and spaced apart from and surrounding the central contact upon the end contact carrier in this end of the shell and also surrounding the sliding contact engageable with this central contact, a motion limiting formation upon this sliding contact permitting engagement of this sliding contact with this central contact when the end contact carrier for this central contact engages its inner bayonet

slot seat and preventing such engagement when this end carrier engages its outer bayonet slot seat; a spring interposed between the intermediate contact carrier and said cup-shaped abutment to maintain this abutment in engagement with the last mentioned end contact carrier when held in either of its bayonet slot seats, said cup-shaped abutment and the sliding contact it surrounds having interengagement that prevents this sliding contact and abutment from becoming separated but permits the cup-shaped abutment to maintain engagement with the last mentioned end contact carrier while held in the outer seat of its two seated receiving bayonet slot.

In witness whereof, I hereunto subscribe my name this 1st day of Aug., A. D. 1917.

HARRY A. DOUGLAS.
